HAT BLOCKING MACHINE

Joseph Bonjokian, Watertown, Mass.

Application October 15, 1937, Serial No. 169,202

6 Claims. (Cl. 223—26)

This invention relates to hat blocking machines and has for one of its objects to provide a novel hat blocking machine which is constructed so as to facilitate the operation of blocking a hat.

5 A further object of the invention is to provide a novel hat blocking machine which is constructed so that it will block equally well hats of various types such as felt hats, Panama hats, ladies' hats, etc.

10 A still further object of the invention is to provide a novel hat blocking machine which is very easy to operate.

15 Other objects of the invention will be apparent from the following description of one embodiment of the invention.

In the drawings wherein I have illustrated a preferred embodiment of the invention;

Fig. 1 is a perspective view of a hat blocking machine embodying my invention with the envelope or cover for the block removed;

Fig. 2 is a vertical section through a hat blocking machine embodying my invention;

Fig. 3 is the envelope or hood which is placed over the adjustable block;

25 Fig. 4 is a fragmentary perspective view showing the supporting member for the block with the block removed;

Fig. 5 is a fragmentary perspective view of the block-expanding element;

30 Fig. 6 is a fragmentary perspective view showing the housing for the adjusting wheel and the screw-threaded member for adjusting the block;

Fig. 7 is a perspective view of one of the sections of the block.

35 The block body, which is indicated at 1, is expandable or adjustable so that it can be made to fit hats of different sizes. This block body is mounted on a suitable support 2 which is shown as provided at its lower edge with a flange 3

40 that is bolted to the top of the housing member 4. The housing member 4 in turn is carried by a suitable stand 5. As stated above, the block body 1 is adjustable or expandable and for this purpose it is made with a plurality of separate

45 sections 6 which are capable of moving radially toward and from each other to vary the size of the block. These sections 6 will preferably be made of metal, and in order to provide a smooth exterior surface for the block to fit with-

50 in the hat I propose to enclose the sectional block body in a hood or envelope 7 which is shown in Fig. 2. This envelope may be made of fabric or rubber or of any other suitable material which can stretch more or less and it will

55 preferably be formed with an elastic neck por-

tion 8. The elastic neck portion 8 is capable of stretching sufficiently to permit it to be inserted over the block body 1, and when the envelope 7 is in place on the block body the neck 8 of the envelope is situated below the block 5 body and its elastic qualities cause it to contract so as to hug the portion 9 of the supporting member 2.

The hood 7 is divided into sections 10 corresponding to the sections 6 of the block body, 10 and the sections 10 of the hood are connected by strips or zones 11 which span the grooves or openings 12 between the sections 6 of the block. These portions 11 of the hood are reinforced or are made sufficiently stiff in any usual or known 15 way so that they form a proper support for the hat opposite the spaces 12 between the sections 6 of the block. The hood 7 thus presents a plurality of sections 10 of elastic or stretchable material which overlie the sections 6 of the block 20 body and said hood also presents the relatively stiff re-inforced zones 11 situated between the hood sections 10 and connecting the latter, which relatively stiff zones 11 overlie and span the joints or spaces between the adjacent block sections 6. When the block body is expanded the hood sections 10 will stretch or expand and the relatively stiff zones 11 form a nonyielding support for the hat in the spaces between the expanded block sections. 30

Each section 6 of the block body is constructed as shown in Figs. 1, 3 and 7. It is formed with a lower face 12 which rests on the top face 13 of the support 2, and it is also formed with a depending flange 14 which is received in a slot 35 15 formed in the top plate 13 of the support 2, there being a slot 15 for each of the sections 6. The depending flange 14 of each block has two wings 16 extending laterally therefrom, one on each side thereof, and these wings underlie the 40 plate 13 and thus hold the block section 6 from vertical movement while permitting it to move radially. The support 2 is in the form of a cylinder and the wall of the portion 9 of the support is formed with openings 17 to receive 45 the wings 16.

Suitable means are provided for expanding the block by moving the block sections 6 outwardly, and as this is done the sections 10 of the hood 7 become stretched. The block-expanding means 50 herein shown comprises a block-expanding element 18 (see Fig. 5) in the form of a head 19 having fingers or bars 20, one for each block section 6, rising therefrom. Each bar or finger 20 is tapered and has an inclined outer edge 21. 55

These bars pass through the slots 15 in the plate 13, as shown in Fig. 4, and the inclined edge 21 of each bar engages the inner face of the corresponding block section, while the back side of each bar operates in a groove 50 formed in a hub or core member 49 that rises from the support 2. Each block section is provided on its inner edge with two ribs 22 that embrace the corresponding bar or finger 20. The block-expanding member 18 is capable of vertical movement, and it will be understood that when said member is moved upwardly the inclined edges 21 of the fingers 20 will act on the inner faces of the various block sections 6 and force said sections outwardly. During this operation the block sections 6 are prevented from vertical movement by engagement of the wings 16 with the under face of the plate 13.

As stated above, the expanding of the block causes the sections 10 of the envelope 7 to be stretched thus placing it under tension. When the block-expanding member 18 is lowered the elasticity of the sections 10 of the hood 7 causes the hood as a whole to contract, which causes the block sections 6 to be moved inwardly as the fingers or bars 20 recede so that the block sections are always held against the inclined edges 21 of said bars. The block is thus expanded to increase its size by moving the block-expanding member 18 upwardly and is contracted to reduce its size by moving the member 18 downwardly.

For thus raising and lowering the block-expanding member 18 the latter is formed with a depending stem 23, the lower end of which is screw-threaded as shown at 24. This screw-threaded portion 24 extends through and has engagement with interior screw threads 25 formed in the hub 26 of an adjusting wheel 27 that is housed within the housing 4. This housing 4 is open on two sides thereby exposing a portion of the rim of the adjusting wheel so that the operator may readily actuate the wheel. The hub portion 26 of the wheel is provided with extensions 28 which are rotatably supported in roller bearings 55 supported in the upper and lower walls 29 and 30 of the housing 4. The stem extends clear through the wheel and at its lower end it has a head 31 of non-circular shape which fits within the correspondingly shaped bore 32 of a sleeve 33 that is secured to and depends from the housing 4. The non-circular shape of the head 31 and the bore 32 prevents the stem 23 from turning so that the rotation of the wheel 27 will simply cause the stem and the block-expanding member to move upwardly or downwardly, depending on whether the size of the block is to be increased or decreased.

Associated with the block-expanding member is an indicator to indicate the size of the block in any adjusted position. This indicator is in the form of a pointer 34 which is secured to the stem 23 and extends radially therefrom, and which is of sufficient length so that the end projects through a vertical slot 35 formed in the wall of the support 2. This support 2 is provided with graduations 36 at one or both sides of the slot 35, these graduations being marked to indicate the size of the block when the pointer 34 is opposite any particular graduation. For instance, if it is desired to adjust the block for a "7" hat then the wheel 24 will be operated to bring the pointer 24 opposite the "7" graduation.

With this construction the size of the block can be increased by turning the wheel 27 so as to force the block-expanding member 18 upwardly

which will result in forcing the block sections 6 outwardly, and the size of the block can be decreased by turning the wheel 27 in the opposite direction so as to move the block-expanding member downwardly. As said block-expanding member is thus moved downwardly the elasticity of the hood 7 serves to force the blocks 6 inwardly and keep them in contact with the receding inclined edges 21 of the fingers 20.

Each block section 6 is shown as having a depending apron 37 at its front side, which apron covers the depending flange 14 and wings 16 and also covers the openings 17 in the support 9.

My improved hat blocking machine is also provided with means for steaming a hat while on the block or for heating the block in case a hat is being treated which requires to be heated rather than steamed. The steam is supplied to the block from any suitable source of supply through the medium of a steam pipe 38 which is shown as extended through the housing 4 above the wheel 27 and then up through the hollow support 2 and into the bore of the hub 49 which forms a backing for the fingers or bars 20. At the upper end of the hub 49 is a manifold 40 which communicates with the bore 39 and which has a plurality of radially extending discharge nipples 41, said nipples extending into the hollow block sections 6 at the upper ends thereof.

The steam pipe 38 will be provided with a suitable valve controlling the admission of steam thereto, and if desired this valve may be capable of operation by a treadle which, when depressed, will open a valve to supply steam to the pipe 38, and which when raised or released will close the valve.

If a hat is being blocked which requires the use of steam for steaming the hat then I propose to use a hood 7 which is more or less porous so that the steam may readily percolate through the walls of the hood. Such an envelope is illustrated in Fig. 2 wherein the shaded portion of the hood sections 10 represents the porous character of the hood 7. Each block section 6 may also be provided with a multiplicity of apertures 42 to provide for the circulation of steam therethrough. With the porous envelope 7 in use the steam will percolate through the block body and through the envelope and thus perform the desired steaming operation on the hat. On the other hand, if it is desired to heat the hat, without steaming it, as in the operation of bleaching a Panama hat, then I propose to use a hood 7 made of impervious but elastic material such, for instance, as rubber. When such a hood is used the admission of steam to the inside of the block and the hood will heat the latter, but because of the impervious character of the hood no steam will percolate therethrough and thus the effect of the steam will be to heat the hat without steaming it.

The standard 5 is shown as hollow and the housing 4 is illustrated as having a depending hollow boss 43 into which the upper end of the stand 5 is screw-threaded.

My improved hat blocking machine is not only useful in blocking hats when they are to be cleaned or re-finished, but is also useful in manufacturing hats, especially felt hats. For manufacturing the felt hats of a given size it is simply necessary to operate the adjusting wheel 27 so as to expand or contract the block to the required size and then to place the felt hat on the block and steam it and then shape it to the size and shape of the block.

While I have illustrated a selected embodiment

of my invention I do not wish to be limited to the constructional features shown.

I claim:

1. A hat blocking machine comprising a stand, 5 a box-like frame supported thereon, a hollow block-supporting member mounted on the frame, an adjustable block carried by said block-supporting member, a block-expanding member adapted by its vertical movement to expand the 10 block, said member having a non-rotatable screw-threaded stem depending therefrom and extending through both the hollow support and the box-like frame, and an adjusting wheel having screw-threaded engagement with said stem, said wheel 15 being journaled in said box-like frame and being held thereby from movement in the direction of its axis.

2. A hat blocking machine comprising a sectional block, a hollow cylindrical support there- 20 for provided in its wall with a vertical slot, a block-expanding member adapted by its vertical move- 25 ment to expand the block, said member having a depending screw-threaded stem extending through the hollow support, an adjusting wheel having screw-threaded engagement with said 30 stem and by which the block-expanding member is raised and lowered, and an indicator connected to said stem and extending through the slot in the support to indicate the size to which the block is adjusted.

3. A hat blocking machine comprising a stand, a hollow block-supporting member mounted thereon, an adjustable block carried by said block-supporting member and provided with a plurality 35 of block sections, a block-expanding member having inclined faces engaging the block sections, said member having a depending stem extending through said block-supporting member, an adjusting wheel having screw-threaded engagement with said stem and capable of turning move- 40 ment but held against movement in the direction of its axis, whereby rotation of the wheel moves the block-expanding member vertically thereby thereby expanding the block.

4. A hat blocking machine comprising a stand, 45 a hollow block-supporting member mounted thereon, an adjustable block carried by said block-

supporting member and provided with a plurality of block sections, a block-expanding member having inclined faces engaging the block sections, said member having a depending stem extending through said block-supporting member, an ad- 5 justing wheel having screw-threaded engage- 10 ment with said stem and capable of turning move- 15 ment but held against movement in the direction of its axis, whereby rotation of the wheel moves the block-expanding member vertically thereby 10 expanding the block, and a steam pipe extending through the block-supporting member into the block and terminating near the upper end there- 15 of, and a steam-distributing manifold having a plurality of radially extending discharge nipples 15 with which the steam pipe communicates.

5. A hat blocking machine comprising a stand, a hollow block-supporting member mounted thereon, an adjustable block carried by said block-supporting member and provided with a plurality 20 of block sections, a block-expanding member having inclined faces engaging the block sections, said member having a depending stem extending through said block-supporting member, an ad- 25 justing wheel having screw-threaded engagement 30 with said stem and capable of turning movement but held against movement in the direction of its axis, whereby rotation of the wheel moves the block-expanding member vertically thereby 35 expanding the block, and size-indicating means car- 40 ried by the stem.

6. A hat blocking machine comprising a sec- 45 tional block, a hood enclosing the block, said hood being divided into sections corresponding to those of the block and the hood sections being formed 35 of elastic material, and said hood also having zones of relatively stiff material interposed between the elastic sections and connecting the same, which zones overlie and span the spaces between the block sections, and means to expand the block, 40 said elastic hood sections stretching when the block is expanded and causing the hood to hug the block as the latter is expanded or contracted, and the zones of relatively stiff material forming a firm support for the hat at the joints between 45 the block sections.

JOSEPH BONJOKIAN.
